SKIVING MACHINE

Francis L. Brandt, Marblehead, Mass., assignor to
 United Shoe Machinery Corporation, Borough
 of Flemington, N. J., a corporation of New
 Jersey

Application May 13, 1939, Serial No. 273,475

12 Claims. (Cl. 12—17)

This invention relates to skiving machines and is herein illustrated as embodied in a machine for removing the forepart of the sole of a worn shoe, preparatory to repairing the shoe by attaching a new forepart.

A common procedure in repairing a worn shoe, the sole of which is attached by cement, is to pull or tear the forepart of the sole from the shoe and then to sever the sole back of the ball line by a bevel cut preparatory to attaching a new forepart, the rear margin of which has been beveled to match the bevel on the sole. With this procedure, however, it is difficult, particularly when the cement is one having exceptionally strong bonding power, to remove the forepart of the worn sole, in such manner as to provide on the exposed bottom of the shoe a smooth surface to which a new forepart may be firmly and evenly cemented.

20 The general object of the present invention is to provide a machine by which this operation may readily be performed. To this end, there is provided, in accordance with one feature of the invention, a knife, a presser, a shoe holder adapted 25 to enter the shoe and to support the forepart of the sole, and means for causing the knife to enter the sole and to remove a skiving from the entire width thereof. In the illustrated machine, the shoe holder is rocked to present the shoe toe 30 foremost to a stationary knife and a cooperating presser roll, two members being provided which extend beneath the projecting margin of the sole at opposite sides of the shoe and support the margin as the sole is progressively presented to 35 and moved past the knife and the presser roll.

These and other features of the invention, including certain details of construction and combination of parts, will be described as embodied in an illustrated machine and pointed out in the 40 appended claims.

Referring to the accompanying drawings,

Fig. 1 is a front elevation of a machine in which the present invention is embodied;

Fig. 2 is a side elevation of the machine; and

45 Fig. 3 is a section on an enlarged scale showing a shoe in process of having the forepart of its sole removed.

The machine comprises a frame, including two upright posts 7 and a crossbar 8. Mounted for 50 vertical sliding movement in vertical slots in the upper ends of the posts are journal boxes 11 for the shaft 13 of a presser roll, the work-engaging portion of said roll consisting of a thick layer of yielding material 15 (Fig. 3), such as rubber, 55 which encircles and is fast to a metal core 17.

The journal boxes 11 are urged downward at all times by two compression springs, one of which is shown at 19, said springs extending up into sockets formed in the crossbar which is fastened at each end to the tops of the posts by screws 21. In the drawings, the presser roll occupies its lowest position in which further downward movement of the journal boxes 11 is prevented by contact of the lower faces of said boxes with shoulders formed at the junction of the lower ends of the vertical slots in which the journal boxes 11 are slidable with the upper ends of narrower vertical slots in which certain blocks, later to be described, are slidable. The knife 21 is fastened to a bracket on the posts by screws, one of which 15 is indicated at 23.

In order to present a shoe to the roll and knife in such manner that practically all of the forepart of the sole of the shoe shall be removed, there is provided a shoe holder which is adapted 20 to enter a shoe 100 and to engage substantially all of the forepart of the insole when this holder is rocked to present the forepart of its sole 200 progressively to the knife and roll. The shoe holder comprises a carrier 29 of the shape shown, 25 a curved plate 31 detachably fastened by screws 33 to a curved face formed on the carrier 29, and a curved handle 35 terminating in a ball 37, which can be readily grasped by the operator to rock the shoe carrier about a horizontal axis, the location of which will presently be described. A series of plates like the plate 31, but of different sizes, is provided, any one of which can be substituted for the plate 31 so as to support the greater part of the foreparts of soles of different sizes. 30 The lower screw remains at all times in place in the holder 29, said screw passing through a slot, the lower end of which is large enough to permit the head of the screw to pass through it. The upper end of the slot is of full width for a depth 40 sufficient to receive the head of the screw, the rest of the upper end of the slot being just large enough to receive the stem of the screw. This construction permits removal and replacement 45 of plates without removing the lower screw.

In order to support the projecting margin of the sole as the sole is presented progressively to the knife and roll, two members 39 are provided, said members being located beneath the presser roll and having beveled ends adapted to be received in the crease between the upper 300 and the sole. Since these supports for the projecting margin of the sole are both mounted in the same manner, only the mounting of one of them will be described in detail. The right-hand member 50 55

39 (Fig. 1) is formed at the outer end of a cylindrical stem 40, which is horizontally slidable in a bore in a block 42, vertically slidable in a vertical slot in the post 7, said stem having at 5 its outer end a cylindrical head 44 which is horizontally slidable in a larger alined bore formed in an extension of said block. A compression spring 47 held against the head 44 by a cap 49, which is threaded over the outer end of the extension, urges the supporting member 39 toward the left, and a screw 51 carried by the head and extending through a long slot 53 in the extension of the block prevents the supporting member from turning. The left-hand member 39 is 10 mounted in the same manner, the vertically slid- able block in which its stem is horizontally slid- able, the small screw for preventing the stem from turning and the cap which holds a spring against the head at the outer end of the stem having been given the same numerals, increased 15 by 100, as those of the corresponding parts of the right-hand support 39. The two supports 39 are thus urged at all times toward each other, but will be moved apart when a shoe is forced 20 between them and will be held beneath the projecting margin of the sole at opposite sides of the shoe during the operation of the knife.

The shoe carrier is rocked about a horizontal axis, which is located at some distance beneath 30 the presser roll and the position of which can be varied. In the position shown in the drawings, this axis is indicated at X. It is the longitudinal axis of a long eccentric 55 formed on the middle portion of a horizontal shaft 57, the left-hand 35 end of which (Fig. 1) extends through a bore in the left-hand post 7 and the right-hand end of which extends through a bushing 59 carried by the right-hand post. The shoe carrier 29 has a long hub, which is rotatably mounted on the eccentric 55 and extends crosswise of the machine from one post 7 to the other. The shaft 57, which carries the eccentric 55, has pinned to one end a hub 61 provided with an upwardly extending handle 63 and a downwardly extending segment 65 having a segmental slot 67 through 40 which extends a locking screw 69, said screw being threaded into one of the posts 7. With this construction the shaft 57 may be rotated into and locked in different angular positions to vary the 45 location of the horizontal axis X about which the shoe carrier is rocked, the purpose of thus varying the height or level of the axis X being to vary the depth of cut of the knife.

The blocks 42, 142 in which are mounted the 50 members 39 for supporting the projecting margin of the sole are vertically slidable, said blocks having reduced middle portions which have a sliding fit in vertical slots formed in the posts 7. In the position of parts shown, these two blocks 55 occupy their lowest positions. When, however, the shoe carrier 29 is rocked to present the sole of a shoe to the knife and presser roll, these blocks are pushed up and in their upward movement encounter and push up the bearing blocks 60 61 of the presser roll against the force of the compression springs 19. In order to cause the blocks 42, 142 to be moved up, the shoe carrier 29 is provided with two cams 129 which contact 65 respectively with the under sides of projections formed respectively upon the lower portions of the blocks 42, 142. These cams, it will be noted, have curved faces, the centers of curvature of which lie in the axis X about which the shoe holder is rocked.

70 Assuming that the axis X has been located at

the proper level to locate the cut where it is desired to be made in the sole of a shoe which the operator has placed upon the shoe carrier as indicated in Fig. 2, the operator grasps the ball 37 and rocks the shoe carrier clockwise to present 5 the shoe toe-foremost between the sole margin supports and to lift the blocks 42, 142 and with them the bearings of the presser roll. As the rocking continues, the knife makes its cut. Referring to Fig. 3, in which the dash line A indicates the cut of the knife, it will be seen that the sole, which in the illustrated shoe has been considerably worn in the middle portion, is pressed by the yielding roll firmly against the shoe carrier and the sole margin supports 39, so that 10 practically all of the forepart of the sole is removed by a cut which extends the full width of the sole, the knife emerging from the sole well back of the ball line due to the longitudinal curvature of the sole, that is to the curve or 15 "break" of the sole to the rear of the ball line. The length of the forepart of the sole, that is the distance from the "break" to the toe end of the sole, is greater than the length of the supporting face of the curved plate 31 so that, at the end 20 of the cut, a portion of the sole to the rear of the ball line is curved down below the surface of the curved plate and, as stated above, the knife emerges from the sole.

Although the invention has been set forth as 30 embodied in a particular machine, it should be understood that the invention is not limited in the scope of its application to the particular machine which has been shown and described.

Having described my invention, what I claim 35 as new and desire to secure by Letters Patent of the United States is:

1. A machine of the class described having in combination a fixed knife, a yieldingly mounted presser, a shoe holder adapted to enter the forepart of a shoe and to support the forepart of the sole, and means for producing relative movement between the holder and the knife and presser lengthwise of the shoe to present the forepart of the sole toe foremost progressively to the 40 knife and presser.

2. A machine of the class described having in combination a knife, a presser of resilient material, a shoe holder adapted to enter the forepart of a shoe and to support the forepart of the sole, and means for producing relative movement between the holder and the knife and presser to present the forepart of the sole progressively to the 45 knife and presser.

3. A machine of the class described having in combination a knife, a yieldingly mounted presser roll of resilient material, a shoe holder adapted to enter the forepart of a shoe and to support the forepart of the sole, and means for producing relative movement between the holder and the knife and presser to present the forepart of the sole progressively to the 50 knife and presser.

4. A machine of the class described having in combination a fixed knife, a presser, and a shoe holder adapted to enter a shoe and to support the forepart of the sole, said shoe holder being rotatable to present the forepart of the sole toe foremost progressively to the knife and presser.

5. A machine of the class described having in combination a knife, a presser, a shoe holder adapted to enter a shoe and to support the forepart of the sole, said shoe holder being rotatable to present the forepart of the sole progressively to the knife and presser, and means for varying the location of the axis of rotation 70 75

of the shoe holder to vary the depth of the cut of the knife.

6. A machine for removing the forepart of the sole of a shoe preparatory to repairing the sole having in combination a fixed knife, a presser roll of resilient material, springs for permitting the roll to yield, a shoe holder rotatable about an axis located beneath said knife and roll and adapted to enter a shoe, said holder comprising a curved supporting surface of an outline similar to that of the forepart of the insole of the shoe, and means for rotating said shoe holder about said axis.

7. A machine for removing the forepart of the sole of a shoe preparatory to repairing the sole having in combination a fixed knife, a presser roll of resilient material, springs for permitting the roll to yield, a shoe holder rotatable about an axis located beneath said knife and roll and adapted to enter a shoe, said holder comprising a curved supporting surface of an outline similar to that of the forepart of the insole of the shoe, and two members for supporting the projecting margin of the sole, said members engaging the sides of the shoe and being mounted for yielding movement away from each other transversely of the shoe.

8. A machine for removing the forepart of the sole of a shoe preparatory to repairing the sole having in combination a knife, a presser, a shoe holder adapted to enter the forepart of a shoe, means for producing relative movement between the shoe holder and the knife and presser to cause the knife to enter the sole and to remove a skiving therefrom, means for supporting the projecting margin of the sole, and means responsive to said relative movement for causing the margin-supporting means to force the margins of the sole against the presser.

9. A machine for removing the forepart of the sole of a shoe preparatory to repairing the sole having in combination a knife, a yieldingly mounted presser roll of resilient material located above the knife, two members for supporting the projecting margin of the sole of a shoe, said

members being located below the knife, a shoe holder adapted to enter the forepart of the shoe, means for moving the shoe holder to present the sole of the shoe progressively to the knife and roll, and means movable with the shoe holder for moving the margin-supporting members toward the knife and the roll away from the knife.

10. A machine for removing the greater part of the worn forepart of the sole of a shoe preparatory to repairing the sole having in combination a fixed knife, a presser roll of resilient material, springs for permitting the roll to yield, a shoe holder rotatable about an axis located below said knife and roll and adapted to enter a shoe, two members for supporting the projecting margin of the sole, said members engaging opposite sides of the shoe and being mounted for yielding movement away from each other, means for rotating said shoe holder, and means operated by said rotation for raising the margin-supporting members and through them the presser roll against its springs.

11. A machine for splitting off the greater part of the forepart of the sole of a shoe preparatory to repairing the sole having in combination a knife, a presser, a shoe holder adapted to enter a shoe and to support the forepart of the sole, leaving the rear part unsupported, and means for producing relative movement between the shoe holder and the knife to cause the knife to enter the edge at the toe end of the sole, to split the forepart of the sole and to emerge to the rear of the ball line.

12. A machine for removing the forepart of the sole of a shoe preparatory to repairing the sole having in combination a knife, a presser roll of resilient material, springs for permitting the roll to yield, a shoe holder rotatable about an axis located beneath the knife and roll and adapted to enter the shoe, said holder comprising a curved shoe-engaging surface, means for rotating the holder about the axis, and means operated by such rotation to raise the presser roll against the force of the springs.

FRANCIS L. BRANDT. 45
